UNITED STATES PATENT OFFICE.

WILLIAM H. MALLORY, OF BRIDGEPORT, CONNECTICUT, ASSIGNOR OF ONE-HALF OF HIS RIGHT TO THOMAS F. ROWLAND, OF NEW YORK.

TORPEDO-BOAT.

SPECIFICATION forming part of Letters Patent No. 223,855, dated January 27, 1880.
Application filed June 28, 1879.

To all whom it may concern:

Be it known that I, WILLIAM H. MALLORY, of Bridgeport, county of Fairfield, State of Connecticut, have invented a new and useful Improvement in Torpedo-Boats, of which the following is a full, true, and exact description, reference being had to the accompanying drawings.

My invention relates to short-range free-going torpedo-boats, which are intended to be substituted for the ordinary torpedo-boom carried on torpedo-launches. These boats contain within themselves sufficient propulsive power to run a short distance—say five or six hundred feet—and are so constructed as to travel through the water in the direction in which they are pointed. By this means it becomes unnecessary to run the torpedo-launch as close to the vessel to be blown up as was previously the case, because this torpedo, when started, will itself, from its own power, traverse the distance between the launch and the vessel to be blown up.

Various attempts have before now been made to accomplish a similar purpose—as, for instance, in the Whitehead torpedoes, manufactured in England, which run by compressed air, and are provided with an automatic steering apparatus. These torpedoes are, however, complicated and expensive, and when in action do not follow a straight line, but rather a series of curves.

My improved torpedo-boat, on the contrary, is very simple, its motive power being obtained from a series of coiled springs, whereby rotation around its own axis, like a rifle-bullet, is obtained, insuring great accuracy of aim. This revolution, moreover, is the natural result of the motive power, as will be presently explained, and the rapidity of revolution is controlled by means of wings or fins.

The general construction of my improved torpedo-boat is as follows: The shell itself consists of a long cigar-shaped vessel—say twelve or fifteen feet in length and ten inches in diameter; but these proportions may be varied. The propelling power is a centrally-located screw-propeller, which is mounted on a ring about the center of the boat, and is provided with a suitable number of propeller-blades.

This ring is attached to one end of a coiled spring similar to an ordinary clock-spring, but of course much heavier.

The inner end of this spiral is connected with a metallic double-connecting drum, which joins it to the outer end of an adjacent parallel coiled spring similar to the first. There is a series of these sufficient to give the number of rotations which may be required to advance the boat the distance designed. They are so connected together that the inner end of each spring is connected to the outer end of the next, or vice versa, so that the total number of revolutions which can be given to the propeller-wheel depends on the number of turns which each spring is capable of producing multiplied by the number of springs. In this way we get a great capacity for rotation from a series of springs coiled in a cylinder having a very small diameter, their effect, however, being the same as that of a single spring, one end of which is attached to the propeller, the other to the boat.

It will be plainly seen that a boat so contrived must have a tendency to revolve in the opposite direction from that in which the propeller is moving, owing to the reaction between the propeller and the boat. This tendency is utilized in my improved torpedo-boat by allowing the spring to give to the boat a rotation about its own axis, and this rotation is controlled by means of fins or wings attached to the stern of the boat, which allow it to rotate about one and one-half turn in advancing its own length, and serve also as a base for the spring to act against in rotating the propeller.

My boat consists, generally, of three sections, connected together by a central tube, the bow or front end being provided with the explosive, the stern or rear end containing a coil of exploding-wire, if one is required.

The details of my boat will be clearly understood from the accompanying drawings, in which—

Figure 1 represents a general view of my boat suspended in what is known as the "gun," which consists simply of an open tube sufficiently large to allow the boat to move freely through it.

B represents a double conical or cigar-shaped boat. The center section or ring is made movable, and is provided with parallel blades P.

S represents a series of springs, constructed as described, and shown more clearly in Figs. 2 and 3, which represent sections through said springs.

The propeller P should preferably be placed about the middle of the boat.

C represents a coil of wire in a compartment communicating with the water. This coil of wire C is so arranged that the twist which is naturally given to the wire in uncoiling is compensated by the rotation of the propelled boat in the opposite direction, so that when the wire is uncoiled to its full length it is practically untwisted, which is not true in the case of a boat not revolving around its own axis, unless some special arrangement is made to counteract the twist due to the uncoiling of the wire. This is continued out of the stern of the boat and forward into the magazine M in the bow. This magazine is also provided with a firing pin, N, and may be fired in connection with the wire, or independently, as may be desired.

The springs are arranged in a series of metallic drums. (Shown in detail in Fig. 4.) The springs are coiled alternately inside of the outer flange and outside of the inner flange, and are connected in series, as shown, so that the outer spiral or coil of each spring is connected inside of the outer flange, while its inner coil is connected outside of the inner flange of the next drum in the series—in other words, the motive power consists of a series of coiled springs, which are connected together by double drums, (shown in Fig. 4,) the outer end of one spring being connected to the inside of the drum, while its inner end is connected to the spindle of the next drum.

It will thus be seen that each of these drums containing springs has a capacity of revolution independent of the others; but they are so connected that the propeller-blades will revolve as many times as all the springs are capable of being wound.

The propeller is prevented from revolving when the apparatus is not in use by means of a key, K, which passes through the stationary part of the boat and through the revolving propeller-ring.

The springs may either be wound by revolving the propeller by hand, or, the propeller being locked by the key K, the worm-wheel U, provided with a suitable revolving stem, may be revolved at the other end, the last drum S' of the series being connected with a cylinder revolved by said worm-wheel, as shown.

The end compartments are connected by the central tube, T, through which the firing-wire R may pass, and the stern is provided with blades W, previously described. The water is allowed to enter the spring compartments and the wire compartments freely; but the series of springs are protected from any external injury by the free sheathing V outside, which extends as far as the revolving propeller-

ring. The propelling-ring is arranged approximately in the center of the lateral resistance of the boat, so that there is no tendency to slue the boat in either direction, which might be the case if it were placed at the stern or at any other position.

The operation of my boat can now be readily understood. The boat B is first placed in the gun G, which is suspended by means of the swivel H at the side or end of the launch. The launch having been brought within striking distance, the proper direction is given to the gun and the key K is withdrawn from the propeller, the springs having been previously wound. The boat immediately assumes a central position in the gun, and passes freely through it in a direction coincident with its axial line.

By depressing the tube the boat can be caused to strike at any distance under water. After leaving the gun the boat follows a straight line in the direction in which it started, and assumes a rotation around its own axis equal to a turn and a half in moving its own length and opposite to the direction in which the propeller is moving, or a rotation approximately equal to that due to the fins W.

In striking the vessel the firing-pin N is driven in, and this may either directly fire the charge or it may be used to make an electrical connection between the wire R and the boat, thereby firing the charge.

It is evident that the rotating fins may be used in connection with other means of propulsion than that here shown; also, that the coiled springs could be used to operate a screw-propeller at the stern; and various other modifications might be made without interfering with the principle of my invention.

I do not wish to be understood as claiming the application of any spring-power mechanism to a shaft of a boat-propeller for the purpose of propulsion; nor do I claim the particular spring-power mechanism described, irrespective of its application to the centrally-located shaft of a torpedo-boat.

What I claim as my invention, and desire to secure by Letters Patent, is—

1. The combination, in a torpedo-boat, with a centrally-located propeller-wheel, of a spring-power mechanism arranged axially therein—that is to say, with the axis about which the springs are coiled coincident with that of the torpedo-boat, substantially as shown and described, whereby rotating translatory movement is imparted to the boat in a true rectilinear direction, as herein set forth.

2. In a torpedo-boat provided with a propeller-wheel as the motive power, the herein-described spring mechanism, the same consisting of a series of coiled springs, which are connected together by double drums, as shown and described, the outer end of one spring being connected to the inside of the drum, while its inner end is connected to the spindle of the next drum, and the end one of the series being connected with the propeller-wheel, the several

drums of said spring mechanism being arranged with their axes coincident with that of the torpedo-boat, substantially as shown and set forth.

5 3. In a torpedo-boat, the combination, with a central propeller and spring-power mechanism to actuate the same, of spirally-arranged fins permanently attached to the rear end of the boat, so that rotation around its axis may give to the boat when in motion a direction opposite to that of the propeller, thereby maintaining it on a direct unvarying course through the water, substantially as set forth.

4. A torpedo-boat provided with a propeller-wheel and with spirally-arranged wings astern of the center thereof, as described, permanently attached to the boat, for the purpose of allowing the boat to assume a determined rotation in the opposite direction to that in which the propeller is moving, substantially as described.

5. A torpedo-boat provided with a centrally-arranged propeller-wheel, and with spirally-arranged wings permanently attached to the boat, for the purpose of allowing the boat to assume a determined rotation in the opposite direction to that in which the propeller is moving, substantially as described.

6. In the combination with a rotary torpedo-boat, a firing-wire coiled in the same direc-

tion as that in which the torpedo itself is revolved, whereby said wire is delivered un-twisted, substantially as described.

7. A torpedo-boat consisting of two independent floating sections and a central connection, which serves to maintain a permanent relation between these sections, and also as a passage for the firing-wire between said sections, substantially as described.

8. A free torpedo-boat provided with a propeller and a locking mechanism or key extending from the fixed portion of the hull into the hub of the propeller, preventing the rotation of the propeller-wheel until withdrawn by the operator, substantially as described.

9. In combination with a free torpedo-boat, a swivel tube or gun, connected with a device, as described, for suspending the same beneath the surface of the water, for the purpose of suspending and giving direction to the torpedo-boat, the said tube or gun being adapted to be turned in all directions irrespective of the position of the launch or vessel from which the tube and contained torpedo-boat are suspended, substantially as described.
